POCKET CONSTRUCTION

Fred Burch, Milford, Mich., assignor to Van Dresser Specialty Corporation, Detroit, Mich., a corporation of Michigan

Original application May 30, 1930, Serial No. 457,633. Divided and this application June 18, 1931, Serial No. 545,333

9 Claims. (Cl. 296—44)

This invention relates to a pocket and to a method for forming the same and has particular reference to a pocket which is associated with a panel or the like.

5 One of the primary objects of this invention is to provide a pocket which will be neat in appearance, simple in construction and which will be resiliently maintained in closed position.

10 The invention contemplates the provision of a method by which a pocket having the above characteristics may be economically formed and contemplates a method which may be efficiently carried out on a commercial scale.

15 This application is a division of my copending application, Serial No. 457,633, filed May 30, 1930.

Numerous other objects and advantages of my invention will become more apparent as the following description proceeds, particularly when reference is had to the accompanying drawing,

20 wherein:

Fig. 1 is an elevational view of a pocket constructed in accordance with the teachings of this invention showing the same associated with a panel;

25 Fig. 2 is a sectional view taken substantially on the line 2—2 of Fig. 1;

Fig. 3 is a semi-diagrammatic elevational view showing the pocket in partly finished condition; and

30 Fig. 4 is a detail perspective view of one of the elements utilized in the forming of the pocket.

A pocket constructed in accordance with the teachings of this invention will find particular utility when associated with a panel of a motor vehicle such, for example, as a door panel or the panel forming the back of the front seat of the vehicle. The invention will thus be described as embodied in a pocket adapted for this use, although it is to be understood that the inventive principles may be utilized in forming pockets other than those incorporated in motor vehicles.

40 The method forming the subject matter of this invention consists broadly in first forming a small auxiliary panel, this panel being small as compared to the size of the panel with which the pocket is to be associated. This small auxiliary panel is covered with suitable upholstery material and constitutes the rear wall of the pocket.

45 The next step in the method consists in forming the front wall of the pocket, and this front wall is formed by cutting a piece of material to substantially the size and shape of the pocket desired, this front wall being preferably cut from the same material as that utilized for covering

across the top edge of the piece of material which constitutes the front wall of the pocket, and this hem is shirred on a resilient member which is then fixed at its ends to the auxiliary panel. The remaining three sides of the front wall of the pocket are then stitched to the auxiliary panel with the result that a pocket is formed closed on three of its sides by a line of stitching and resiliently held closed at its top by the resilient member.

5 The main panel is then formed to the size and shape desired, and an opening is blanked out in this panel corresponding to the size of the pocket desired. This main panel is then upholstered and is placed over the small auxiliary panel, with the opening in the main panel in alignment with the pocket formed on the auxiliary panel. The portion of the main panel adjacent the opening formed therein will conceal the free edge of the front wall of the pocket and will also conceal the line of stitching which secures the front wall of the pocket to the auxiliary panel. The opening in the main panel is made sufficiently large to permit access to the pocket through the top thereof, as will be readily apparent.

10 Referring then particularly to the drawing wherein like reference characters designate corresponding parts throughout all views, a pocket constructed by the above method is disclosed as comprising a small auxiliary panel 11 which is covered with suitable upholstery material, as designated by the reference character 12. The front wall 13 of the pocket is cut to substantially the size and shape of the pocket desired from a piece of material preferably similar to the material utilized in covering the panel 11. A hem 14 is formed in the upper edge of the front wall 13 of the pocket, and this hem is shirred on a longitudinally extensible member such as the coil spring 15, it being noted that the convolutions of this 15 spring are closely adjacent to each other, thus increasing the resiliency of this member.

20 The ends of the coil spring 15 are anchored to the face of the panel 12 by clips 16 and tabs 17, one of these clips and tabs being shown in detail 25 in Fig. 4 of the drawing.

25 These securing members constitute an important feature of the invention, and it will be noted that each clip 16 comprises a single piece of wire bent to form a leg 20 and a side 21 bent to extend at substantially right angles to this leg. The end 22 of the side 21 is return bent as at 23 and lies adjacent the free end 24 of the side 25 which is bent to extend at an inclination upwardly from the lower end of the side or leg 20. The ends 30

23 and 24 together provide a hook with which the adjacent end of the coil spring 15 may be engaged, as clearly illustrated in the drawing.

Each tab 17 comprises a piece of tape folded 5 around the leg 20 of its respective clip. Each tab is secured to the panel by means of a staple or the like 30 which passes through the double thickness of the tape and then through the panel, this staple having its free ends bent in the rear 10 of the panel, as clearly illustrated in Fig. 2 of the drawing. Each tab is also secured to the panel as by stitching, this stitching being designated by the reference character 31 in Fig. 3 of the drawing.

15 After the coil spring 15 is anchored in position by the tabs 17, the free edge 35 of the front wall of the pocket is stitched to the auxiliary panel by the line of stitching designated by the reference character 36. The main panel 37 is then 20 blanked out to form an opening 38 of the size and shape of the pocket, and this main panel is covered by a suitable upholstery material designated by the reference character 39. The panel 37 is then placed over the auxiliary panel with 25 the opening 38 opposite the front wall 13 of the pocket, the arrangement being such that the portion of the panel 37 surrounding the opening 38 conceals the line of stitching 36, the securing members 16 and 17 and the free edge of the front 30 wall 13.

It will be noted that the coil spring will be held in juxtaposition to the auxiliary panel by the members 16 and 17 and will thus function to maintain the top of the pocket closed. Further, the hooks formed on the clips by the ends 35 23 and 24 of the wire are located adjacent the tops of the clips so that the coil spring 15 will be held in position adjacent the upper edge of the hem 14 of the front wall of the pocket. The 40 clips thus provide a simple and efficient means for holding the coil springs in position whereby these springs function to maintain the tops of the pockets closed.

From the above it will be apparent that the 45 invention provides an improved method of forming a pocket and an improved pocket for use with a panel or the like. The pocket is resiliently held closed by spring means, and this spring is in turn fixed in position by clip members which 50 are simple in construction and which may be readily affixed to the panel.

The main panels with which the pockets are associated may be formed of cardboard or the like, as is customary in the forming of door panels, or may be formed of metal such as is used 55 in forming the back of the front seats in vehicles. Still further, the pockets may be incorporated in vehicle bodies or may be utilized wherever it is desired to form pockets associated with panels. 60 By utilizing a coil spring for closing the top of the pocket, the necessity of using a rubber strip for this purpose is eliminated, and the danger of the pocket closing means losing its elasticity is decreased to a considerable extent.

65 While the invention has been described with some detail, it is to be understood that the description is for the purposes of illustration only and is not definitive of the limits of the inventive idea. The right is reserved to make such changes 70 in the steps of the method as well as the order thereof and in the details of construction as will fall within the purview of the attached claims.

What I claim as my invention is:

1. In a pocket construction, a substantially 75 rigid panel constituting the rear wall of the pock-

et, a front wall for said pocket secured along three of its sides to said panel and having a hem formed in its fourth unattached side, a coil spring in the hem in said front wall, a clip hooked to each end of said coil spring, and a tape looped around each clip and secured to the panel. 5

2. In a pocket construction, a substantially rigid panel constituting the rear wall of the pocket, a front wall for said pocket secured along three of its sides to said panel and having a hem formed in its fourth unattached side, a resilient member mounted in the hem in said front wall, a clip secured to each end of said resilient member, and a tape secured to each clip and to said panel. 10

3. In a pocket construction, a panel constituting the rear wall of the pocket, a front wall secured along three of its sides to the said panel and having a hem formed in its fourth unattached side, a longitudinally extensible resilient member mounted in the hem in said front wall, a pair of clips, each clip having a hook portion engageable with one end of said longitudinally extensible member and having a leg portion, a tape looped about the leg portion of each clip, and means for securing each tape to the panel, whereby said longitudinally extensible member is anchored at its end to the said panel. 15 20

4. In a pocket construction, an auxiliary panel constituting the rear wall of the pocket, a front wall stitched along three of its sides to the said auxiliary panel and having a hem formed in its unattached side, a longitudinally extensible member mounted in the hem in said front wall, means including clips fixing the ends of said longitudinally extensible member to said auxiliary panel, and a main panel positioned over said auxiliary panel, said main panel having an opening opposite said front wall, the portion of said main panel surrounding said opening concealing the edge of the front wall of the pocket and the clips for securing said extensible member to said auxiliary panel. 30 35 40

5. In a pocket construction, a panel forming the back of the pocket, a piece of material forming the front of the pocket and secured along three of its sides to the said panel, a resilient cable associated with the unattached side of said piece of material to hold the same adjacent the said panel, and means for securing the ends of said resilient cable to said panel, said means including a single piece of wire bent to form a clip having an elongated leg portion and having a hooked portion adjacent one end of said leg portion, and a tape looped around the leg portion of said clip adapted to be secured to the said panel. 45 50 55

6. In a pocket construction, the combination with a panel forming the back of the pocket and a resilient cable for holding the top of the pocket adjacent the said panel, of means for anchoring each end of said cable to said panel, said means including a single piece of wire bent to form a vertically extending leg portion, a second portion extending at substantially right angles to said leg portion at the upper end thereof, said last mentioned portion being return-bent to form a hook adjacent the upper end of said leg portion, said wire being bent at the lower end of said leg portion to form a side extending diagonally from said leg portion to adjacent the return-bent portion associated with the top of said leg portion, said side being return-bent to form a hook portion adjacent said first mentioned hook portion, and a piece of flexible material looped about the leg 60 65 70 75 80 85 90 95 96

portion of said wire and adapted to be secured to the said panel.

7. In a pocket construction, front and rear walls secured to each other along three of their sides, a resilient member engageable with the unattached side of one of said walls, a clip secured to each end of said resilient member, and a tape for securing each clip to the other of said walls adjacent the unattached side thereof.

10 8. In a pocket construction, a panel constituting the rear wall of the pocket, a front wall for said pocket secured along three of its sides to said panel, a resilient member engaging the unattached side of said front wall, a clip secured to each end of said resilient member, each clip having a hooked portion secured to its respective end of the resilient member, and means for securing said clips to the panel.

9. In a pocket construction, a panel constituting the rear wall of the pocket, a front wall secured along three of its sides to the said panel and having a hem formed in its unattached side, a longitudinally extensible member mounted in the hem in the said front wall, means for fixing the ends of said longitudinally extensible member to said panel, and a second panel positioned over said first mentioned panel, said second mentioned panel having an opening opposite said front wall, the portion of said second mentioned panel surrounding the opening therein concealing the edge of the front wall of the pocket and the means for securing said extensible member to the first mentioned panel.
